Attorney

UNITED STATES PATENT OFFICE.

CHARLES P. BURGESS, OF BETHESDA, MARYLAND.

AIRSHIP CONSTRUCTION.

Application filed January 28, 1925. Serial No. 5,397.

To all whom it may concern:

Be it known that I, CHARLES P. BURGESS, a citizen of the United States, residing at Bethesda, Maryland, have invented new and useful Improvements in Airship Constructions, of which the following is a specification.

This invention relates to improvements in airship construction and more particularly to construction in bracing of the inner shell within which the gas bag is contained.

In hitherto known forms of gas cell wiring the lift of the gas in a frame space between main and intermediate transverse frames is transmitted by the wiring and the longitudinals to the main and intermediate frames in nearly equal proportions; and the greater part of the weight loads are either suspended from the main frames or carried to them by the keel, so that the lift of the gas transmitted to the intermediate frames produces a rise and distortion of these frames with respect to the main frames; and there results an undesirable bending in the longitudinal girders, and large loads upon the shear wires between the main and intermediate frames.

In the present invention it is proposed to obviate the above mentioned objections to known methods by providing a system of gas cell retaining netting composed of wires of which all or the greatest part slope upward from the main frames towards the intermediate frames, transmitting the greater part of the gas lift directly to the main frames. A secondary system of inclined or longitudinal wires or cordage may also be provided, secured to the principal wires for the purpose of maintaining the correct spacing, and assisting in the support or restraint of the gas cells.

A further object is to provide a simple and practical means for constructing and bracing the frame of an airship which will not involve increase in expense yet greatly increase the efficiency, strength and durability of the frame.

Other objects will be in part obvious and in part hereinafter pointed out in connection with the accompanying sheet of drawings wherein is illustrated semi-diagrammatically a small section of the frame with the bracing wires associated therewith.

In this drawing 1 indicates one of the intermediate transverse or circumferential frame members extending entirely about the

airship while 2 indicates the main frames also extending entirely about the airship. These main frames are connected by longitudinals 3 at spaced intervals; and extending upwardly from the main frames towards the intermediate frames are a series of diagonally disposed gas cell retaining wires 4. Additional brace wires 5 parallel to the longitudinals may be employed.

Heretofore it has been customary to arrange these brace wires in criss-cross formation from one longitudinal to another. Other constructions have involved circumferential wires parallel to the main and intermediate frames. The theory of the proposed improved construction may be more readily understood by comparing this system of wiring illustrated in this application with the former conventional diagonal mesh or circumferential mesh or system above mentioned.

In the present arrangement the tension in the inclined wires exerts downward forces on the intermediate transverse frames 1 with respect to the adjacent main frames 2 thereby opposing the shear force which tends to lift the intermediate frames when the conventional systems of wiring, that is, the diagonal criss-cross or circumferential wiring is used.

It should be especially noted that whereas in the former conventional construction no resistance to the lift of the intermediate frames can occur until they have risen out of alignment with the neighboring main frames, in the present system of wiring the tension produced in the netting or bracing wires by the gas pressure resists the shearing force between the main and intermediate frames even when there is no relative movement between them.

It follows that with the former conventional construction there must always be a distortion of the intermediate frames and consequent bending of the longitudinals but with the present system the distortion and bending are practically eliminated.

It will thus be seen that by providing a construction as herein shown and described, that is, in which all or the greater part of the gas cell returning wires extend upwardly from the main frames to the intermediate frame, the objections heretofore explained are eliminated. The amount of wiring used is substantially the same and there is consequently little or no increase in the expense

of manufacture and installation, yet a far more durable, reliable and efficient construction is obtained.

What I claim is:—

- 5 1. In an airship construction, in combination with a main frame and intermediate frames, a series of gas cell retaining wires extending diagonally upward from the main frames towards the intermediate frame to thereby transmit the gas lift in greater part to the main frames instead of equally to the main and intermediate frames.
- 10 2. In an airship construction, in combination with main frames and intermediate frames, longitudinal girders disposed at substantially right angles thereto, a series of gas cell retaining wires extending in a general direction from the main frames diagonally upward towards the intermediate frame,

thereby to transmit the gas lift in greater part to the main frames, instead of equally to the main and intermediate frames.

3. In an airship construction, in combination with main frames and intermediate frames, longitudinal girders disposed at substantially right angles thereto, a series of gas cell retaining wires extending in a general direction from the main frames diagonally upwards towards the intermediate frames, and additional wires connecting the said diagonal wires, thereby to transmit the gas lift in greater part to the main frames, instead of equally to the main and intermediate frames.

Signed at Washington, District of Columbia, this second day of December, 1924.

CHARLES P. BURGESS.
